CAR PIT FORM

Carl C. Buebke, Portland, Oreg.

Application October 29, 1946, Serial No. 706,315

3 Claims. (Cl. 25—128)

1

This invention relates generally to automobile lifts of the hydraulic type and particularly those employing two vertical pistons.

The main object of this invention is to construct a car pit form whereby a car pit can be easily made and the forms removed therefrom with the least amount of effort and with the expenditure of the minimum amount of time.

The second object is to eliminate entirely the waste of wood which commonly accompanies the making of car pit forms of this type.

I accomplish these and other objects in the manner set forth in the following specification as illustrated in the accompanying drawing, in which:

Fig. 1 is a perspective view of the form showing portions broken away in section.

Fig. 2 is a horizontal section taken along the line 2—2 in Fig. 1.

Fig. 3 is a transverse section taken along the line 3—3 in Fig. 1.

Fig. 4 is a perspective view of one of the angle bars.

Fig. 5 is a perspective view of one of the toggle arms.

Fig. 6 is a section taken along the line 6—6 in Fig. 1.

Fig. 7 is a perspective view of one of the form sides.

Fig. 8 is a fragmentary sectional view showing an extension for a truck lift pit.

Fig. 9 is a perspective view of the extension used for truck lift pits as shown in Fig. 8.

Referring in detail to the drawing, there is shown a pair of rectangular form plates 10 having the inturned bottoms 11 formed thereon which form footings for the form plates 10. Inside of the form plates 10 are welded the vertical ribs 12 of angle bars, whose lower ends 13 are secured to the bottoms 11. The ribs 12 are provided with inclined slots 14 near the bottom and near the middle of the height thereof. Resting on the bottom 11 are the loose stiffening bars 15 which bear against the inner edges of the ribs 12 when the form is set.

The upper end 16 of each rib 12 is offset to form a slot 17 which receives the upper stiffening bars 18.

There are also provided the end members 19 having the inturned sides 20 formed thereon which match with the form plates 10.

In order to move the form plates 10 out to their proper spacing for the purpose of giving the right dimension to the form, I have provided a form expanding and holding mechanism which

2

consists of the upright tie bars 21, across the upper end of which is mounted a lock brace 22 which is in the form of an angle bar, to which are secured by means of rivets or bolts 23 the perforated bars 24, the ends of which are united to the upper ends 16 of the ribs 12 by means of the removable bolts 25 which pass through the holes 26 in the ends 16 of the ribs 12.

Near the middle and at the bottom of the tie bar 21 are the brace bars 27 and 28, to which are attached the extensions 29 by means of the bolts 29A. To each lower member 29 is secured an angle bar 30 which is adapted to engage the interior of the stiffening bar 15.

In the form of the device shown in Figs. 8 and 9, there is provided a T bar 31 which extends along the sides of the form while the extension sides 32 bear against the outside thereof and are preferably provided with a removable end gate 33.

In the form of the device shown in Fig. 9, the extension 32 is provided merely to afford additional height as is necessary when the pit is being constructed for truck lifts.

The operation of the device is as follows: Assuming that an opening 34 has been excavated large enough to receive the setup form as shown in Fig. 1 and to leave enough space around same to receive the aggregate which will go to make up the completed wall 35, the form plates 10 are now lowered into the opening and held in alignment by means of the stiffening bars 15 and 18. The ends 19 are also put into place and the members 21 are lowered into place as shown in Fig. 3, in which the bolts 36 are made to enter the slots 14 and the tie bar 21 forced downwardly, causing the ribs 12 to move away from each other. It will be noted that the angle bars 30 on the extensions 29 of the brace bar 28 engage the inner sides of the stiffening bars 15, whereas the outermost holes 37 in the perforated bars 24 register with the holes 26 in the ribs 12 and they both receive the bolts 38 which are provided with the wing nuts 39, thereby locking the form securely into shape. A reversal of this procedure will naturally make it possible to withdraw the forms.

It will be noted in Fig. 5 that the members 24 are provided with a plurality of bolts 23 which makes possible the moving of the members to a pre-determined dimension.

In the form of the device shown in Fig. 9, instead of employing the stiffening bars 18, I prefer to employ the frame T bars 31, to which are welded the side plates 32. The sides 32 and the end members 33 are united by the bolts 40, which pass through the ears 41 on the side plates 32.

where they are held by means of the wing nuts 42.

I am, of course, aware that numerous forms of car pit forms have been constructed in the past. I, therefore, do not claim such devices broadly but I do intend to cover such forms and modifications thereof as fall fairly within the appendant claims.

I claim:

1. A car pit form having in combination a plurality of sections each of which section consists of a pair of opposite side form plates having inwardly turned bottoms, each of said form plates having secured thereto a pair of vertical ribs, one leg of each rib being normal to the side plate, said leg having inclined notches formed therein near the bottom and middle of the length thereof, the upper end of said leg having a slot formed therein between same and its respective form plate, said slot constituting a pocket for one leg of a stiffening angle bar, closures for the space between the ends of the outermost side forms, and braces for said form consisting of a plurality of toggle links disposed between said ribs and having bolts thereon adapted to engage said inclined notches, a vertical tie bar connecting the toggle joint of said toggle links and a brace bar mounted across the upper end of said tie bar having means for attaching same to the upper end of the ribs, together with stiffening bars along the upper and lower ends of said ribs adapted to hold the panels in longitudinal alignment.

2. In a device of the class described the combination of a pair of upright form plates having inturned bottom edges, a stiffening bar of angular cross section loosely placed upon each inturned edge, each of said form plates having a pair of upright ribs secured thereto having inclined slots formed in the lower end of said ribs and in the middle of the height thereof and having a hole formed in the lower end of said ribs and in the

links mounted between the lowermost inclined slots having bolts mounted therein adapted to engage said slots, said toggle links having angle bars mounted thereunder, adapted to engage said 5 stiffening bars when said toggle is moved toward a straight line position, and a tie bar connecting the joints of said toggle links for the purpose of actuating same.

3. In a device of the class described the combination of a pair of upright form plates having inturned bottom edges, a stiffening bar of angular cross section loosely placed upon each inturned edge, each of said form plates having a pair of upright ribs secured thereto having inclined slots formed in the lower end of said ribs and in the middle of the height thereof and having a hole formed through the upper end of each rib, toggle links mounted between the lowermost inclined slots having bolts mounted therein adapted to engage said slots, toggle links having angle bars mounted thereunder adapted to engage said stiffening bars when said toggle is moved toward a straight line position, a tie bar connecting the toggle joints of said toggle bars for the purpose of actuating same, and a brace member between the upper ends of said form sides consisting of a horizontal bar of adjustable length.

CARL C. BUEBKE.
